UNITED STATES PATENT OFFICE.

AUGUST M. KRUSE, OF DEFIANCE, OHIO, ASSIGNOR TO THE AMERICAN STEEL PACKAGE COMPANY, OF DEFIANCE, OHIO, A CORPORATION OF OHIO.

SHIPPING-CASE.

1,164,364.

Specification of Letters Patent. Patented Dec. 14, 1915.

Application filed April 29, 1914. Serial No. 835,136.

To all whom it may concern:

Be it known that I, AUGUST M. KRUSE, a citizen of the United States, residing at Defiance, in the county of Defiance and State 5 of Ohio, have invented certain new and useful Improvements in Shipping-Cases, of which the following is a specification.

My invention relates to improvements in shipping cases, the present embodiment being particularly designed and adapted for use in the transportation and storage of merchandise packed in containers, cartons, or the like, such for example, as granulated sugar and similar or analogous substances.

15 The invention relates more particularly to improvements in the construction and reinforcement of the upper and lower marginal edges of the case body and means for securing and supporting the lid or cover and 20 bottom in position whereby these portions of the case are greatly strengthened and rendered less liable to injury as well as improving the general construction whereby general strength and stability is given to the case 25 body as a whole.

A further object is the provision of a case of this class having an unobstructed interior whereby the containers or cartons may be readily inserted or removed as well as the 30 provision of an improved reinforced bottom adapted to provide a suitable friction bearing surface as well as preventing the depression or sagging of the bottom by the weight of the superposed case contents.

35 A still further object is the provision of an improved hinged lid or cover having a depending peripheral beading adapted to take over, surround and abut against the beading at the upper edges of the case body 40 when the lid is closed whereby a second strengthening beading is formed about the beading of the case body thus giving general strength and stability to the upper marginal edges of the case when the lid is closed.

45 A still further object is the provision of an improved hinged lid or cover together with improved means for locking and sealing the same in closed position.

With the above mentioned and other ends 50 in view, the invention consists in the novel construction, arrangement, and combination

of parts, hereinafter described, illustrated in one of its embodiments in the accompanying drawings, and particularly pointed out in the appended claims.

55

Referring to drawings, forming a part of this specification, Figure 1, is a perspective view of an improved shipping case constructed in accordance with this invention, the lid or cover being locked and sealed. 60 Fig. 2, an enlarged cross sectional view taken through the lock and hinge portions of the lid or cover. Fig. 3, a cross sectional view of a modified form of hinge.

Similar numerals of reference designate 65 like parts throughout all the figures of the drawings.

The improved case comprises suitable lateral or side and end walls 1, and a bottom wall 2, said lateral walls 1, being preferably 70 curled about a wire 3, to form a bottom supporting and strengthening beading, and as a means for connecting and reinforcing the bottom and lateral walls about the lower marginal edges of the case said bottom wall 75 is preferably bent or curled about the beading at the lower marginal edges of the lateral walls to form a second beading 3^a.

As a means of further strengthening and reinforcing the bottom 2, the latter is preferably 80 crimped into a series or plurality of reinforcing ribs or flanges 2^a, extending up to and abutting against the beading 3^a, said ribs or flanges 2^a, extending flush with the floor engaging portions of the beading 3^a, 85 for the purpose of not only forming a convenient friction bearing surface but of supporting the intermediate portions of the bottom as against sagging from the weight of the superposed case contents.

90 The ribbed bottom wall 2, is similar in form and formation to the ribbed walls disclosed and claimed in Kruse Patent No. 870,728 of November 12th, 1907, and for the purpose of this application need not be further described in detail.

95 The upper marginal edges of the lateral walls 1, are curled over and about a wire 4, forming a lid supporting beading 5.

The lid or cover 6, is provided about its 100 marginal edges with a depending beading 6^a, inclosing a strengthening wire 7, said

beading 6^a, being adapted to entirely surround and abut against the lid supporting beading 5, when the lid is closed as shown most clearly in Fig. 2 of the drawings whereby a second strengthening beading is formed outside of the beading of the case body and is adapted to further strengthen and reinforce the beading at the top of the case body.

As a means of hinging the lid or cover 10 6, to the case body, one side of the cover is provided with a pair of hinge straps 8, each strap comprising a single length of sheet metal bent upon itself and midway of its ends to form a hinge loop 8^a, taking over 15 the lid supporting beading 5, of the case and the strengthening wire 7, of the lid, the ends of each strap being secured by a rivet 8^b, as shown most clearly in Fig. 2 of the drawings. Certain portions of the material of the lid supporting beading 5, and cover beading 6^a, corresponding in width to 20 the width of the hinge straps are cut away forming hinge strap receiving recesses 8^c, to receive and contain the hinge loop portions 8^a, of the hinge straps. If desired, however, the loop portion 8^a, of the hinge strap may be formed only about the strengthening wire 7, of the beading 6^a, of the lid or cover as shown in Fig. 3 of the drawings. 25

As a means of securing the lid or cover in its closed position the free side of the latter may be provided with latch or hasp members 9, terminating at their free ends in hooked loop heads 9^a, said members 9, being 30 pivotally secured to the lid or cover 6, by being curled over and about the wire 7, of the lid or cover 6, and being mounted in cut-away recesses 9^b, in a manner similar to the mounting and securing of the hinge straps 8, hereinbefore described.

As a means of securing the loop heads 9^a, of the latch or hasp members 9, in closed or locked position guide securing brackets 10, are provided, said brackets being provided with openings or recesses 10^a, at their front to receive and contain the hooked heads or loop eyes 9^a, of the latch members 9, when the latter are in their closed or locked position, and as a means for directing 50 and pressing the hooked heads forwardly to snap into engagement with the recesses or openings 10^a, of the bracket members as well as securely maintaining the members 9, in engagement with the brackets, bowed spring 55 members 11, are secured to the case body at the rear of the members 9, and in the present instance, arranged within the brackets 10. It will be seen that the loop heads 9^a, when within the openings or recesses 10^a, of the brackets 10, form wire receiving loop eyes through which sealing wires 12, are adapted to pass and which wires 12, may be passed at the rear of the members 9, and be secured by means of seals 13, so that the

case contents are thereby securely sealed. 65 When it is desired to detach the latch or hasp members 9, the loop heads 9^a, may be readily pressed out of engagement with the openings 10^a, of the brackets by the thumbs of the hands while the latter are in engagement with the adjacent front corners of the case and as the hooked heads are pressed rearwardly against the resistance of the springs 11, the loop heads 9^a, may be simultaneously pressed upwardly to partially elevate the free edge of the lid or cover in the act of releasing the head 9^a, from the brackets 10.

From the foregoing description, taken in connection with the accompanying drawings, the operation and advantages of my invention will be readily understood.

Having thus described one of the embodiments of my invention, what I claim and desire to secure by Letters Patent, is,—

1. In a shipping case, the combination with a case body provided about its upper marginal edges with a lid supporting beading; of a hinged lid or cover provided with a depending peripheral beading surrounding and abutting against the latter in substantially the same plane and inclosing a reinforcing wire, and hinge and hasp straps pivotally mounted on said reinforcing wire of said lid or cover whereby the latter is secured in its closed position, said hinge and hasp straps being secured to said case body below said lid supporting beading and abutting against the same.

2. In a shipping case, a case body having 100 a rectangular shaped lid supporting beading inclosing a wire and a cover having a similarly shaped beading inclosing a wire, said cover normally resting on said lid supporting beading, and said cover beading fitting 105 down outside of and surrounding and abutting against said lid supporting beading in substantially the same horizontal plane when the lid is closed, said cover beading being also provided at one side with a pair of cut-away hinge strap receiving recesses, and hinge straps bent mid-way of their ends forming hinge loops resting in said hinge strap receiving recesses and extending about said wire inclosed by said cover beading, 110 said hinge straps extending beneath and abutting against the outer sides of said lid supporting beading and being secured to the case body beneath said lid supporting beading.

3. In a shipping case, the combination with a case body having the upper marginal edges of its lateral walls curled about a reinforcing wire forming a lid supporting beading, and a lid resting on the latter and having its marginal edges curled about a reinforcing wire forming a second beading abutting against and resting in substantially

the same horizontal plane with said lid supporting beading; of hinge straps secured to one of said lateral walls below and abutting against said lid supporting beading 5 and passing around the reinforcing wire within said beading of said lid.

In testimony whereof I have affixed my signature in presence of two witnesses.

AUGUST M. KRUSE.
